DESIGN FOR A FISH LURE

Karl R. Larson, Minneapolis, Minn.

Application July 24, 1939, Serial No. 86,205

Term of patent 14 years

To all whom it may concern:

Be it known that I, Karl R. Larson, a citizen of the United States, residing at Minneapolis, in the county of Hennepin and State of Minnesota, have invented a new, original, and ornamental Design for a Fish Lure, of which the following is a specification, reference being had to the accompanying drawing, forming part thereof.

Fig. 1 shows the fish lure in perspective;

Fig. 2 shows the fish lure in plan, looking at the top thereof;

Fig. 3 shows the fish lure in side elevation; and

Fig. 4 is a section taken on the line 4—4 of Fig. 3.

I claim:

The ornamental design for a fish lure, as shown.

KARL R. LARSON.
